EXPANSIBLE LINK CHAIN FOR A BRACELET
OR THE LIKEEmil Rodriguez, New York, N. Y., assignor to
Jacoby-Bender, Inc., New York, N. Y., a corpo-
ration of New York

Application June 11, 1951, Serial No. 15,489

Term of patent 7 years

(Cl. D45—4)

To all whom it may concern:

Be it known that I, Emil Rodriguez, a citizen of the United States and a resident of New York, county and State of New York, have invented a new, original, and ornamental Design for an Expansible Link Chain for a Bracelet or the like, of which the following is a specification, reference being had to the accompanying drawing forming a part thereof, in which:

Fig. 1 is a top view of the expansible link chain in contracted condition showing my new design, portions of the conventional bottom links visible at the ends of the chain being shown in broken lines;

Fig. 2 is a top view thereof in partially expanded condition, portions of the conventional bottom links being visible between the top links and shown in broken lines;

Fig. 3 is a side elevational view on an enlarged scale, of one of the individual top links of the chain of Fig. 1;

Fig. 4 is an end elevational view of the individual top link of Fig. 3; and

Fig. 5 is a top plan view on an enlarged scale of one of the individual top links of the chain of Fig. 1.

I claim:

The ornamental design for an expansible link chain for a bracelet or the like, as shown.

EMIL RODRIGUEZ.
